Primary Examiner — Amber R Stiles*Assistant Examiner* — Earl B Elowsky(57) CLAIM

The ornamental design for a hand shower, as shown and described.

DESCRIPTION

FIG. 1 is a front, right, and top perspective view of a hand shower showing my new design;

FIG. 2 is a rear, left, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the hand shower that form no part of the claimed design.
